Patented Jan. 10, 1967

206,650

CABINET FOR A SHOE POLISHING MACHINE

William A. Beck, River Hills, and William F. Kruke, Cedarburg, Wis., assignors to Beck, Inc., Grafton, Wis.,
a corporation of Wisconsin

Filed Oct. 11, 1965, Ser. No. 87,416

Term of patent 14 years

(Cl. D9—2)

Fig. 1

Fig. 4

Fig. 3

FIG. 1 is a front perspective view of a cabinet for a shoe polishing machine showing my new design;

FIG. 2 is a side elevation of the cabinet;

FIG. 3 is a front elevation of the cabinet; and

FIG. 4 is a top view of the cabinet.

The rear of the cabinet is plain.

The broken lines shown on the drawings are for illustrative purposes only.

We claim:

The ornamental design for a cabinet for a shoe polishing machine, as shown and described.
